UNITED STATES PATENT OFFICE.

ABBOTT B. DAVIS, OF SAUGATUCK, MICHIGAN.

TOY DUCK.

1,392,485.

Specification of Letters Patent.

Patented Oct. 4, 1921.

Application filed July 29, 1920. Serial No. 399,818.

To all whom it may concern:

Be it known that I, ABBOTT B. DAVIS, a citizen of the United States of America, residing at Saugatuck, in the county of Allegan and State of Michigan, have invented certain new and useful Improvements in Toy Ducks; and I do hereby declare the following to be a full, clear, and exact description of the invention, such as will enable others skilled in the art to which it appertains to make and use the same.

This invention relates to a toy, specifically a toy duck, though the invention is not limited to the one form shown and hereafter described. It is an object and purpose of the present invention to construct a toy, having the form of an animal and provided with means whereby it may be propelled over the floor, coupled with which the toy is made to go through certain motions simulating the operation of feeding, all being attained with a simple construction, very economical to make so that the marketing may be at a low cost. Various other objects and purposes will appear fully and in detail as understanding of the invention is had from the following description, taken in connection with the accompanying drawing, in which,

30 Figure 1 is a side elevation of the toy.

Fig. 2 is a vertical section taken longitudinally and centrally therethrough, and

35 Fig. 3 is a vertical transverse section taken substantially on the planes of the broken line 3—3, of Fig. 2.

Like reference characters refer to like parts in the different figures of the drawing.

In the construction, two sides 1 are made of wood and cut in the form of the body of the animal chosen, the same being spaced apart and between which adjacent their lower edges a member 2, preferably of lead is placed and secured permanently. A block 3 is placed between the sides at the rear upper part thereof and also permanently secured in place. At the front upper portion, a combined neck and head portion 4 is placed between the sides 1 and pivotally connected at its lower end thereto, being adapted to 45 turn on the pivot pin 5. A block 6 simulating any desired figure is placed between the sides back of the neck and head portion 4 and extends above the sides, being pivotally connected to and between the sides 1 at its lower end and adapted to swing on the pivot

pin 7 as shown. Tie rods or similar means are used to connect the forwardly reaching arms of the figure 6 with the part 4, preferably with the bill portion thereof as shown in Figs. 1 and 2.

60 A shaft 9 extends through the sides 1 above the weight 2 and at each end is equipped with a wheel 10, one of which at least is permanently connected to the shaft. Both may be, if desired. Between the sides 1, the shaft is bent to form a crank 11. A stirrup 12 extends downwardly from the neck and head portion 4 and a link 13 connects the lower portion of said stirrup with the crank 11.

70 Rods or wires 14 are loosely connected to the shaft 9 one between each wheel 10 and the adjacent side of the body, the same extending upwardly and to the rear and being bent toward each other and formed into a 75 handle 15. Any other desired type of handle may be attached to the ends of the rods 14, as is evident.

75 The toy may be run over any smooth surface, the turning of the wheels serving to 80 turn the shaft 9, with each revolution of which, the neck and head portion 4 is oscillated back and forth once about its pivot 5, due to the connection through stirrup 12 and link 13 of said member 4 with the crank 85 11. On the forward movement of the member 4, its weight serves to partly overbalance the body, which also tips forward, but on the return, the weight 2 serves to right the body. The movement is practically an 90 exact simulation of the feeding movements of the animal which the toy represents, and in the continued movement of the toy in a forward direction, such movements are periodically repeated. The toy is impelled forward, or may be drawn back, by grasping the handle 15 and imparting the proper force thereto.

95 The movements of the neck and head portion 4 are simultaneously accompanied by 100 like movements of the figure 6 due to the connection between them made by the members 8. This figure shown at 6 may be left off if desired.

105 The construction is simple and economical to manufacture. The form of the animal simulated may be changed without departing from the invention as is evident. The appended claims define the invention, and I consider myself entitled to all forms of 110

structure that come within the scope of these claims defining the invention.

I claim:

1. A toy comprising a body having spaced apart sides, a weight secured between the sides at the lower portion of the body, a shaft extending through the body and formed with a crank portion between said sides of the body above the weight, a neck and head portion pivotally connected at its lower end to the body between the sides thereof, a stirrup extending downwardly from the said head and neck portion, a link connecting the stirrup with the crank portion of the shaft, wheels connected with the ends of the shaft, and means for propelling the toy over the floor, said weight normally holding the body in upright position, substantially as described.
2. A toy comprising a body having spaced apart sides, a weight secured between said sides at the lower portion of the body, a shaft extending through the body above the weight, a neck and head portion pivotally connected at its lower end to the front upper portion of the body, wheels attached to the shaft, one at each end thereof, means for propelling the toy over the floor, and means connecting the shaft and head and neck portion whereby said portion is oscillated back and forth about its pivot on rotation of the shaft, said weight permitting oscillation of the body about the axis of the shaft but normally keeping it in an upright position, substantially as described.
3. A toy comprising a body, a weight attached to the body at its lower portion, a neck and head portion pivotally connected to the body at its front upper portion, a shaft extending through the body and formed with a crank in its length, means operatively connecting said crank with the neck and head portion whereby on rotation of the shaft, the head and neck portion is oscillated about its pivot, and wheels attached to the shaft for turning the same on movement of the toy on said wheels, said

weight controlling the movements of the body, substantially as described.

4. A toy comprising a body, a shaft extending through the body, a weight attached to the body below the shaft, wheels on the shaft, a neck and head portion pivotally connected to the body, means formed on the shaft and means connecting said means with the head and neck portion for oscillating said portion about its pivot on rotation of the shaft, said weight serving to control the movements of the body about the axis of the shaft, substantially as described.

5. A toy containing the elements in combination defined in claim 4, combined with a figure block pivotally connected at its lower end to the body back of the head and neck, and means connecting said block with the neck and head portion for simultaneously oscillating said block therewith.

6. A toy containing the elements in combination defined in claim 4, combined with a figure block pivotally connected at its lower end to the body back of the head, and a rod connecting the head with said figure block, substantially as and for the purposes described.

7. A toy comprising a body having spaced apart sides, a weight secured between said sides at the lower portion of the body, a shaft extending through the body above the weight and formed with a crank portion between the sides of the body, wheels attached to the shaft to turn the same, a neck and head portion pivotally connected at its lower end to the body between the sides thereof, means connecting the crank with the neck and head portion for oscillating said portion with rotation of the crank, a rod loosely attached to the shaft at each side of the body and extending rearwardly therefrom, and a handle formed at the ends of the rods, said rods being bent together back of the body, substantially as described.

In testimony whereof I affix my signature.

ABBOTT B. DAVIS.
